UNITED STATES PATENT OFFICE.

ANNA S. TURNQUIST, OF MINNEAPOLIS, MINNESOTA.

DESIGN FOR A BRACELET.

Application filed September 19, 1927. Serial No. 23,463. Term of patent 3½ years.

To all whom it may concern:

Be it known that I, ANNA S. TURNQUIST, a citizen of the United States, residing at Minneapolis, in the county of Hennepin and State of Minnesota, have invented a new, original, and ornamental Design for Bracelets, of which the following is a specification, reference being had to the accompanying drawing, forming part thereof.

Fig. 1 is a plan view of a bracelet showing my new design.

Fig. 2 is an edge view of two links of the bracelet showing the thickness of the bracelet.

I claim:

The ornamental design for a bracelet as shown.

In testimony whereof I hereunto affix my signature.

ANNA S. TURNQUIST.
